UNITED STATES PATENT OFFICE.

GEORGE H. STRONG, OF CHICAGO, ILLINOIS.

CABINET FOR ADVERTISING PURPOSES.

SPECIFICATION forming part of Letters Patent No. 530,668, dated December 11, 1894.

Application filed December 26, 1893. Serial No. 494,627. (No model.)

To all whom it may concern:

Be it known that I, GEORGE H. STRONG, a citizen of the United States, residing at Chicago, in the county of Cook and State of Illinois, have invented new and useful Improvements in Cabinets for Advertising Purposes, of which the following is a specification.

This invention relates to improvements in cabinets for advertising purposes particularly intended for post offices.

The object of the invention is to cheapen the construction of such cabinets, and make them more efficient for the purposes intended.

The invention consists substantially in the construction illustrated in the accompanying drawings, described in the specification and hereinafter more particularly pointed out in the claims.

Like letters refer to the same parts in the several figures of the drawings, in which—

Figure 1 is a front elevation of a cabinet mounted upon a pedestal with part of such pedestal broken away. Fig. 2 is a horizontal transverse section on the line 2—2 of Fig. 1. Fig. 3 is a vertical section of the main portion of the cabinet on the line 3 3 of Fig. 1. Fig. 4 is a longitudinal cross section in detail of two of the sliding panels and the frame in which they slide with the cards shown in place.

The cabinet is designed particularly for use in post offices and its purpose being to display advertising cards in a pleasing and attractive manner and be so constructed as to be economically manufactured and convenient for the purposes intended.

The cabinet is principally made of wood and may be of rectangular shape, as shown in Fig. 2, and be supported upon a pedestal away from the wall, or it may be of any other suitable shape convenient to be placed against the wall or in a corner. It is designed to be provided with inclined desks such as are designated by the letters B, B, in the drawings and be formed with receptacles for ink wells as designated by the letters C; recesses for penholders as designated by the letters D and other needful accessories for the use of the patrons of the post office who desire to address an envelope or write a postal card or short letter. Among these may be mentioned a letter scale such as is shown at E in Fig. 1

of the drawings. This main cabinet I have designated by the letter A and it is composed of the hollow frame work or box having the top and bottom and vertical partitions arranged as may be desired.

The special feature of the invention is the construction and arrangement of the removable panels for containing the advertising cards and this will now be described.

The top of the main cabinet A has slots G cut vertically through it as shown plainly in Fig. 3, and in dotted lines in Fig. 1. These slots are arranged at such suitable intervals as desired, and for the purpose of permitting the insertion of removable panels containing the advertising cards. These removable panels consist of an independent frame as is shown at the letter H in the drawings which are formed with tongues or projections upon which they slide in grooves or ways formed in the frame A of the cabinet. These frames are preferably divided by horizontal partitions as shown so as to form independent spaces for each advertising card. The cards are preferably made of metal with the advertisement engraved upon their face, and being of a lighter color than the wooden partitions the result is that the different advertisements are perfectly separated so that each business thus advertised is presented distinctly to the eye of the observer. This is of more importance in practice than it would at first seem in theory for it has been noticed that where the advertisements have been arranged upon cards in immediate juxtaposition with no distinct separation between advertisements other than the space on the cards, observers confuse one with the other, and apply to the place of business of one person advertised in relation to the subject matter of another advertisement. These cards may be readily inserted in the panels in any convenient way but are preferably slid from the side in grooves formed in the frame of the panel before such panel is placed in the cabinet. An entire panel may be readily removed and one or all of the cards changed, and this without taking off any cap piece or removing any screws, or the necessity for any implements.

The framework of the movable panels may consist simply of the side and end pieces

and the transverse partition strips which are grooved to receive the advertising cards, the cards themselves forming the main body of the panel, or the panels may be complete 5 in themselves and provided with transverse pockets to receive the cards therein.

By sliding the cards into the pockets in the panels before the panels are inserted in their guideways in the main frame I am enabled 10 to provide a construction whereby transportation is greatly facilitated, as the panels, with the cards are shipped separately from the main body of the cabinet and hence the liability of breakage of the glass fronts of the 15 cabinet is reduced to a minimum.

Upon the top of the main cabinet there may be placed a second smaller case designated by the letter F in the drawings. This smaller case may be formed in one piece with the top of 20 the main case or removably connected therewith. This small case should in any event be placed a sufficient distance back of the edge of the main case to leave uncovered the slots G in which the panels are to be inserted in 25 the main case. The small case may also have advertising cards inserted therein or advertising matter placed on its surface and is usually somewhat ornamental and surmounted by a clock or statuette or something of that 30 nature.

It is obvious that changes may be made in the details of the above described construction without departing from the essential features thereof, which latter have been set 35 forth, and will now be particularly pointed out in the claims.

What I claim as new, and desire to secure by Letters Patent, is—

1. An advertising cabinet comprising a 40 frame having two or more sides or faces, arranged at right angles relative to each other, vertical guide ways or channels formed in each side or face, arranged in pairs, a panel frame adapted to be received removably in 45 each pair of guide ways, said panel frames being provided with independent pockets or compartments, arranged horizontally therein, and adapted to receive advertising cards therein, as and for the purpose set forth.
2. In an advertising cabinet an upright 50 frame or casing, comprising two or more pairs of vertically arranged guide ways, the con-

tiguous or adjacent pairs being arranged angularly relative to each other forming an open framework, removable panels adapted to be received in said pairs of vertical guideways, each panel being provided with a series of transverse independent pockets or compartments adapted to receive advertising cards; as and for the purpose specified. 60

3. In an advertising cabinet a stand, a writing desk supported thereby, a cabinet supported by said desk, comprising an upright frame work, formed of two or more sides or faces arranged at right angles relative to each 65 other, a coping at the top of each side or face forming a seat, a supplementary cabinet adapted to be received on said seat and to receive advertising cards, two or more sets of vertical guide ways formed in each face or 70 side and through said coping in the first mentioned cabinet, a removable panel adapted to be received in each set of guide ways, each having a series of independent transverse pockets arranged therein, adapted to receive 75 advertising cards, said supplementary cabinet arranged out of line with said vertical guide ways, as and for the purpose set forth.

4. In an advertising cabinet a writing desk having ink-wells and pen racks formed therein, and having a seat for a cabinet on the top thereof, a suitable support for said desk, in combination with an upright rectangular frame or casing having the sides or faces thereof cut away as shown, a coping arranged at 85 the top of each side or face, and joining the edge portions and adapted to form a seat, a pair of vertical guide ways formed in each side or face near the edge thereof, said coping having passage ways communicating with said 90 pairs of guide ways, a removable panel adapted to be received in each pair of guide ways, thus forming a recess or compartment in said frame work between said pairs of guide ways, each of said panels being provided with a 95 series of transverse pockets or compartments adapted to receive advertising cards, as and for the purpose set forth.

In testimony whereof I have hereunto set my hand in the presence of two witnesses.

GEORGE H. STRONG.

In presence of—

J. WHITTIER BUFFUM,
BUSHNELL STRONG.
